UNITED STATES PATENT OFFICE.

FREDERICK SIEMENS, OF DRESDEN, SAXONY, GERMANY.

GAS-BURNER.

SPECIFICATION forming part of Letters Patent No. 323,537, dated August 4, 1885.

Application filed February 8, 1884. (No model.) Patented in Germany May 31, 1881, No. 17,342; in England June 17, 1881, No. 2,638; in France June 21, 1881, No. 131,208; in Belgium July 4, 1881, No. 55,086, and in Austria-Hungary, September 10, 1881, No. 18,053 and No. 32,808.

To all whom it may concern:

Be it known that I, FREDERICK SIEMENS, a citizen of Saxony, residing at Dresden, in the Empire of Germany, have invented certain new and useful Improvements in Lamps, of which the following is a specification.

My invention relates to that class of lamps or burners wherein the heat of the products of combustion is imparted to the air or gas to supply for the flame.

In the specification forming a part of Letters Patent of the United States, No. 241,077, dated May 3, 1881, granted to me, a lamp was described which was constructed as follows:

15 An annular burner, consisting of a number of small vertical tubes arranged in circular form and rising from an annular chamber, had its central space formed into a regenerative chamber containing material offering extended surfaces for taking up heat, which chamber communicated at its bottom with a passage leading to the chimney or cylindrical tube, arranged in a line which was a prolongation of the axis of the central regenerative chamber. The latter served for the passage of the products of combustion, which were drawn over its circular upper edge from the annular flame by the draft of the chimney. Entirely surrounding the outside of the burner was an annular chamber 20 which had a circular opening at its lower end, and contained material offering extended surfaces, which became heated by conduction from the heat given off to the central chamber and imparted such heat to the air passing upward on its way to the flame of the burner. As the flame of the burner was drawn from all directions inward directly over the circular edge of the cylindrical chamber, it was necessary to carry this up to such a height as to afford the 25 desired length of flame. For this purpose a separate cylinder of fire-clay or other suitable refractory material was fitted to the upper end of the regenerative chamber.

According to my present invention a flat or 45 ribbed vertical plate, of a width corresponding to the width of burner required, has formed upon it at or about the middle of its height a horizontal closed channel or small chamber, into which the illuminating-gas is led 50 by a pipe, and from which it issues through

a number of small vertical tubes arranged in a row, and which constitute the burner of the lamp. On one side of the before-mentioned plate is formed a flat vertical passage, within which are situated the said gas channel and 55 tubes, and which extends at its upper end to near the top of the tubes, where it is open, and has its outer side provided with a notched deflecting-flange by which the air-supply passing up through the open lower end to the 60 burner is deflected toward the flame and divided into a number of separate jets; or the notches may be dispensed with and the deflecting-flange may be provided with a smooth or straight edge. The said air-supply passage is extended downward some distance below the lower ends of the gas-tubes. On the other side of the first-mentioned flat plate carrying the gas-burner is formed another flat 65 passage extending downward like the air-passage, but which according to one arrangement is closed at bottom, while at the upper part it is divided by a longitudinal partition into two passages, of which the one next the burner is made to open at some height above the burner, 70 while the other or back passage communicates at its upper end with a flue-pipe. That part of the plate carrying the burner, which extends from the tops of the gas-tubes to the opening of the inner passage, is formed of a 75 separate piece of porcelain or other suitable refractory and light-reflecting material, and it has by preference formed on its face next the burner one or more notched ribs, which deflect the air rising from the air-passage on 80 the inner side of the gas-tubes against the inner side of the flame, and which also offer additional surface for taking up heat from the flame.

In the accompanying drawings, in which 90 corresponding parts are designated by similar letters, Figure 1 shows a vertical transverse section of the lamp on the line *a b* of Fig. 2. Fig. 2 is a longitudinal section on the line *c d* of Fig. 1. Fig. 3 is a cross-section on the line 95 *e f* of Fig. 1. Fig. 4 is a horizontal section on the line *g h* of Fig. 5. Fig. 5 illustrates in vertical section a lamp in which the flue-pipe is arranged horizontally.

A is a small chamber into which the illuminating-gas is led.

nating-gas is introduced through the pipe A', and from which it issues through a row of small tubes, C. The chamber A is formed in the flat side B of a passage, F, which constitutes the air-heating chamber or regenerator of the lamp. Behind the said side of this passage is formed the passage D, communicating at bottom with the flue-pipe I, and having at top an opening situated above a plate, P, of porcelain or other suitable refractory material, placed on top of the side B. This plate has two rows of notched projections, K K', and a third row of projections, K'', is formed on the upper edge of the outer side of the air-passage F just below the tops of the gas-tubes C. By means of these projections the air-current passing up through F on each side of the gas-tubes is divided into a number of separate streams and deflected against the flame. Against the outer side of the passage F is by preference formed a second narrow air-passage, H, through which a current of air passes, takes the heat which would otherwise be lost by radiation from the casing of the passage F, and in impinging against the outer surface of the flame serves to steady it.

The action of the lamp is as follows: Gas being admitted into A and ignited at the tubes C, the flame and gaseous products therefrom in passing upward against the surface of the porcelain plate P impart heat to the flue-pipe I, thereby inducing an upward current of air therein, which will cause the flame and gaseous products to be drawn over the edge of the plate P into the passage D, in which they will descend in order to escape up the flue-pipe I. The heat thus imparted to the sides of the passages is transmitted by conduction to the air-passage F, thereby heating the air and gas supply to a considerable degree before entering into combustion. By extending the air-passage downward to some extent, as shown, a column of hot air will be contained therein, which will induce an upward current of sufficient force to enable the flame to burn steadily without a chimney-glass. It is of great importance for this purpose that the column of air in F should be sufficient to produce the requisite current for the flame independently of the chimney-draft. By the passages F and H highly-heated air is fed with considerable impulse against the flame, while the heated gas issues with comparatively low velocity from the tubes C, so that the action obtained is just the reverse of that of ordinary flat gas-burners, in which the steadiness of the flame is obtained by causing the gas to issue with high velocity into a comparatively quiescent surrounding atmosphere. The porcelain plate P also serves as a reflector, so that these flat burners are particularly adapted for throwing the light in one particular direction—such as is required for wall-lights, shop-windows, theaters, picture-galleries, and the like.

As the burner may be constructed with a row of gas-tubes, C, of any desired length,

either arranged in a straight line or in any desired curve, various novel effects in illumination may be produced by means of these lamps, such as are not possible with circular 70 burners.

Having thus described the nature of my invention and in what manner the same is to be performed, I claim—

1. The combination of a straight row of 75 gas-tubes, with a regenerator or passage for heating the air-supply to the flame on one side of a straight or curved division-wall, and a regenerator or passage for taking up heat from the products of combustion on the other 80 side of the said wall, the upper part of which wall extends to a height above the gas-tubes corresponding to the height of the flame, and is formed of porcelain or other refractory material having an aperture for the downward 85 passage of the products of combustion, as and for the purposes described.

2. In a regenerator-lamp, the combination, with the burner, of a plate of porcelain or other refractory and light-reflecting material 90 having one or more rows of notched projections, as and for the purposes described.

3. In a regenerative-lamp, the combination of a plate of porcelain or other refractory and light-reflecting material having one or more 95 rows of notched projections at a certain height above the gas-tubes, with an air-deflecting flange on the other side of the gas-tubes at or above the level of the tops thereof, as and for the purposes described. 100

4. The combination of a series or group of flat regenerative burners with a flue-pipe common to all, as and for the purposes described.

5. In a lamp or burner in which the incoming air and gas and outgoing products of combustion flow in relatively opposite directions, the combination of a number of gas-orifices with a plate of porcelain or other suitable refractory material extending above 110 the orifices and having an opening through which the products of combustion flow on their way to the flue-pipe, as and for the purposes described. 105

6. The combination of the inner passage, 115 through which the products of combustion pass from the flame, the chamber surrounding the burner, through which the air passes, and the plate of porcelain or other refractory material located above and behind the burner. 120

7. The combination of the inner passage, through which the products of combustion pass from the flame, the air-passage surrounding the burner, and an exterior air-passage, which takes up the heat radiated from the 125 casing of the air surrounding the burner, as and for the purposes described.

8. The combination of the inner passage, into and through which the products of combustion pass from the burner, with an adjacent gas-passage communicating with the burner-tubes, whereby the heat of the outflow- 130

ing products of combustion is communicated to the inflowing-gas, as and for the purposes described.

9. The combination of the passages into which the products of combustion are drawn over the plate of porcelain above the burner-tubes and the adjacent flue-pipe communicating with the bottom of the said passage, as and for the purposes described.
10. The flat or ribbed vertical plate B, on the top of which is the plate P, in combination with the passages F and D, as and for the purposes described.

11. The flat or ribbed vertical plate B, having formed upon it a channel into which the illuminating gas is led and from which it is

sues through a number of vertical tubes, in combination with plate P, of porcelain or other refractory material.

12. The combination of the partition-plate 20 B, between the passages D and F, with one or more rows of gas-tubes, C, arranged in front of the partition-plate and communicating with the gas-channel formed thereon, as and for the purposes described.

In testimony whereof I affix my signature in presence of two witnesses.

FREDERICK SIEMENS.
